UNITED STATES PATENT OFFICE.

VINCENZO ALLEGRA, OF NEW YORK, N. Y., ASSIGNOR OF ONE-HALF TO PHILIP S. SAITTA.

STREET-CAR FENDER.

No. 927,441.

Specification of Letters Patent.

Patented July 6, 1909.

Application filed February 24, 1909. Serial No. 479,738.

To all whom it may concern:

Be it known that I, VINCENZO ALLEGRA, a citizen of the United States, and a resident of the borough of Brooklyn, in the county of Kings, city and State of New York, have invented certain new and useful Improvements in Street-Car Fenders, of which the following is a specification.

My invention relates to car fenders and particularly to that class of fenders which are adapted to be operated by contact with the person or object striking the same so as to take up and hold the said person or object and thus prevent him or it from falling beneath the wheels or being thrown from the fender. Its objects are, among others, to provide a fender for the accomplishment of these purposes of simple, strong and durable construction and of quick and reliable action, the parts being so formed and arranged that the device is compact and sightly and not calculated to interfere with traffic, and may also be moved to a position where it is out of operation, or detached and placed at either end of the car.

To these ends the invention consists in the construction, combination and arrangement of parts hereinafter described and claimed and illustrated in the accompanying drawings.

In the said drawings, Figure 1 is a three-quarter front view of one end of a street car with a fender embodying the improvements attached thereto. Fig. 2 is a vertical medial section of the fender detached, the illustration being on a larger scale than that of Fig. 1.

The main frame A consists of a metallic rod or tube bent to form substantially three sides of a rectangle and having its forward lower part bent outward and upward, to better serve the purposes of the device. It is attached to the car by means of hooks or staples G, at its inner and upper ends, which are adapted to pass over the posts or standards H secured to the bumper of the car. These posts are made longer than necessary to hold the fender while in its operating position, in order to give it a certain amount of play, and also to enable them to hold the fender when it is raised out of its said operating position. By simply sliding the frame up until the upper hooks G pass off the top of the posts H, the fender may be placed in a non-operating position, and will remain in such position.

Within the main frame A a supplemental frame B is pivoted in such a manner that its outer and lower edge moves through a wider are than its upper and inner edge. This is 60 accomplished by simply placing the pivot C nearer to the upper side of the frame. When this frame is in its tripped or "sprung" position, it is caught and held by the lever D, which coöperates as a pawl with the teeth E 65 on the side of the frame adjacent thereto. This lever acts as a pawl and has its outer end-turned outwardly and upwardly on the outer side of the main frame A, this outer part being integral with the inner or pawl 70 part which is pressed in the direction of the teeth E by a spring J secured to the side of the main frame, so that as soon as the frame is tripped, the pawl end of the lever will snap into the teeth and prevent it from returning 75 again to its normal position. The lever is pivoted to the side bar of the main frame A.

The inner and upper side of the frame B is connected to the outer and lower side of the main frame A by the rods or wires F 80 which have their upper ends turned around the upper bar of the said inner frame and their lower ends turned through the staples M on the lower bar of the said main outer frame. These rods or wires possess a certain 85 degree of flexibility and the connection between their ends and the two frames is such as to permit of a certain amount of movement. In this manner the connection between the two frames by means of the rods 90 or wires is prevented from interfering with the free and instantaneous movement of the said inner frame when it is "sprung."

The main frame A is provided with a netting K of suitable material stretched thereon, 95 and through this netting the side bars of the frame B pass near the pivot C, the inner and upper bars of the frame being behind the said netting and the lower and outer bars in front of it. Between this lower bar and the lower 100 bar of the main frame A a net L is strung, and this net also extends part way up the sides of the said frames, so as to form a pocket or basket when the inner frame is oscillated to its "sprung" position.

The netting stretched within the main frame forms the back of the pocket, and is always in the same position whereas the netting stretched between the part of the frame B which is in front of the frame A and the 110 lower part of the frame A is folded up when the parts are in their normal position and

stretched when the frame B is sprung, so that it forms the outer part of the said pocket.

The operation of the device is extremely simple and effective; when the body of a person strikes the fender it immediately comes in contact with the upper bar of the frame B or one of the connecting rods F, and the impact causes the said inner frame to rock on its pivots so that its outer portion is thrown up and the pocket of netting thus formed to catch and hold the said person. It will be understood that when the body strikes one of the connecting rods, the frame B will be rocked even though the body does not strike the upper bar thereof, because the upper ends of the said connecting rods are secured to the said upper bar, and the tension on the rods caused by the impact will instantly pull the upper bar down and consequently throw the outer part of the frame B up.

What I claim is:—

1. The combination of a main outer frame, a connection between the said frame and the car, a second frame rocking therein and extending on both sides thereof pivoted within the said main frame, and netting or the like spread between the sides of the main frame.

2. The combination of a main outer frame, a connection between the said frame and the car, a second frame pivoted within the said main frame and extending on both sides thereof, and netting or the like spread between the sides of the main frame, and other netting between the lower and outer sides of the main frame and second frame.

3. The combination of a main outer frame, a connection between the said frame and the car, a second frame pivoted intermediate its ends within the said frame, and netting or the like strung between the sides of the main frame, and other netting between the lower and outer sides of the main frame and second frame, and a flexible connection between the said lower part of the main frame and the upper and inner part of the second frame.

4. The combination of a car, a main fender frame, a connection between the same and the car, a second frame pivoted within the said main frame and a catch adapted to permit the said inner frame to move to a position and locking it against returning.

5. The combination of a main frame attached to the car, a second frame movably mounted within the main frame, netting or the like connecting the lower portions of the said two frames the construction and arrangement of the two frames being such that the impact of the object striking the upright

part of the same causes the inner frame to move and form a pocket of netting between the lower portions of the said frames.

6. In a device of the character described the combination of a main frame, a connection between the said main frame and the car, a second frame pivoted to and adapted to rock on the main frame and mounted in a substantially upright position, rods connecting the upper part of the said second frame and the lower part of the main frame in such a manner as to permit movement of one with respect to the other, the construction and arrangement being such that the impact of a body striking the said rods or upper part of the second frame will cause the same to rock and assume a different position.

7. In a device of the character described the combination of a main frame, a connection between the said main frame and the car, a second frame pivoted to and adapted to rock on the main frame and mounted in a substantially upright position, rods connecting the upper part of the said second frame and the lower part of the main frame in such a manner as to permit movement of one with respect to the other, the construction and arrangement being such that the impact of a body striking the said rods or upper part of the second frame will cause the same to rock and assume a different position, and a lever pivoted adjacent to the pivot of the second frame having one end spring-pressed against the said second frame and adapted to move to a position which will prevent the said frame from returning to its original position after being rocked.

8. In a device of the character described the combination of a main frame, a connection between the said main frame and the car whereby the former is mounted thereon in a substantially upright position, a second frame pivotally mounted on the first frame and adapted to rock vertically thereon, the major portion of the said second frame being below its pivot, whereby the said frame is held normally in a substantially upright position, but will be rocked to position approaching the horizontal by a weight striking the upper part thereof, in which position a portion of the said second frame will project out beyond the main frame.

Witness my hand this 26th day of January, 1909, at the city of New York, in the county and State of New York.

VINCENZO ALLEGRA.
